Application August 23, 1938, Serial No. 226,346
In Germany July 29, 1937

5 Claims. (Cl. 66—98)

The present invention relates to knitting machines and is particularly directed to an improvement devised to prevent or, at least, lessen the formation of disorderly stripes or ribs in the 5 looped fabrics manufactured on flat knitting machines operating with spring needles.

It is a well known fact that knitted goods produced on the aforementioned machines are frequently provided with unsightly longitudinal stripes, which sometimes are called needle or sinker stripes. The cause of these stripes is by no means a secret. They are principally due to the fact that the hooks of the spring needles, which are used in the machines in considerable 10 numbers, are not always exactly alike. Slight variations occur, either in the height of the hooks or in their curved shape or degree of elasticity, and will suffice to cause the formation of the disorderly stripes. It is not sufficient that all of the 15 other series of elements, which in the sinking and dividing section of a flat knitting machine of the type in which the loops of a row of loops are formed by one thread cooperate in forming the loops, such as the sinkers, knock-over bits, 20 jacks and frame needles, are perfectly uniform in size and dimensions. Such uniformity alone will not insure the formation of uniform loops if through variations in the height, curvature or elasticity of the hooks the size of some of the 25 loops is varied at the expense of the size of adjacent loops as soon as the hooks begin to open after the pressure upon them has been released. It is obvious that a hook which is too high, too 30 curved or too strongly elastic must necessarily produce a loop of unusually large size, whereby the excess of material necessary for forming the 35 oversized loop will be pulled from adjacent loops formed on lower or less curved or less elastic hooks, with the result that the adjacent loops 40 will be correspondingly smaller in size. It is further obvious that the same irregularity will recur in each row of loops at the same spot and therefore result in the formation of the aforementioned unsightly longitudinal ribs or stripes. 45 As long as the needle bars are new the differences in the hooks will of course be insignificant, and the stripes for that reason will be hardly noticeable. But after a while the differences will be 50 more pronounced, partly because the constant wear on the needles has reduced the elasticity of some of the hooks more than of others, and partly because of the new needles which had to be substituted for those that had become outright defective.

In order to prevent the more or less unavoidable differences in the shape and elasticity of the hooks from interfering with the formation of uniform loops the applicant proposes to prolong the pressure on the hook and thereby retard its opening-up movement until a moment in which the hook is no longer able to influence through its opening-up movement the size of the loop formed on its needle. This moment has arrived as soon as the loop has slipped over the top of the needle. 10 At this moment the loops just formed can no longer be influenced by any of the solid elements of the machine in such a manner that the size of some of the loops of the row could forcibly be 15 changed with respect to the size of other loops of the row.

The prolongation of the pressure on the rock and retardation of the opening of the latter may be achieved in various ways. For a flat knitting machine of the type in which the loops of one row are formed by one thread (for instance a "Cotton" machine) the applicant proposes the use of a second presser member. According to the invention this second presser member has been arranged below the upper edge of the knock-over sinker, where it performs the function of pressing the hooks of a row of needles against their stems either at a time where the customary pressing 20 action is still going on or immediately following 25 that customary pressing action, for instance at the moment when the loops just formed have slipped onto the hooks and the points of the hooks are between the knock-over sinkers. This additional pressing mechanism should preferably 30 be of such construction that the hooks are kept under pressure until the loops have left the tops of the needles. For this purpose the pressing mechanism should be a movable one and receive 35 its driving impetus either from a special eccentric shaft or from the main shaft with the aid of cams of known description. 40

Through the arrangement of the additional presser means the applicant obtains various important advantages. 45

The principal advantage is the fact that the formation of the disorderly and unsightly longitudinal stripes or ribs is either completely prevented or considerably lessened. 50

Another advantage resides in the feature that the adjusting of the needles done almost exclusively to prevent the formation of stripes and which always takes up considerable time, particularly in old machines, will no longer require 55

that utmost care and not be necessary as frequently as before.

The third advantage is the logical consequent of advantage number two, since fewer and shorter interruptions of the time of production will naturally increase the capacity of production and thereby reduce the price of the finished article.

In other words: through provision of the additional presser mechanism the applicant provides 10 the means of producing a more perfect article with less effort, in a shorter time and at a reduced cost.

The invention is fully disclosed in the following description, of which the accompanying drawing forms a part, and in which similar numerals of reference indicate corresponding parts in all of the figures. However, it is to be understood that the drawing merely illustrates one embodiment of the invention (as applied to a "Cotton" machine) and that variations and modifications which come within the scope of the claims hereunto appended can be resorted to.

In the drawing—

Figs. 1, 1a and 1b are views of frame needles provided with different types of hooks;

Fig. 2 is a view of a portion of the machine showing how the hook of the needle is closed by a presser bar of known construction, with one loop enclosed in the hook and another loop enclosing the stem of the needle just below the point of the hook;

Fig. 3 is a detail view showing the presser bar in withdrawn position, the hook open and the lower loop on the back of the hook;

Fig. 4 is a detail view showing the position of the additional presser member after its pressing action has just begun;

Fig. 5 is a detail view showing the position of the additional presser member at the end of its activity.

Referring more particularly to the drawing the numerals 1, 1', 1'' (Figs. 1, 1a and 1b) represent frame needles provided with various types of hooks 2, 2', 2'', of which hook 2 is normally bent, while hook 2' is unusually outwardly curved and hook 2'' of a somewhat flattened formation. Mounted on the main shaft 3 (Fig. 2) of the machine is a cam 4 which at periodical intervals acts upon a roller 6, mounted on a lever arm 7 of the double-armed lever 7, 7', pivoted at 13. Lever arm 7 is spring-controlled by spring 5 and, owing to the action of cam 4 upon roller 6, is forced against the tension of spring 5 in the direction indicated by the arrow A, while lever arm 7' is simultaneously swung in the opposite direction. The lever arm 7' is formed of thin metal plates or fingers, of which each one extends with its free end 7'' into the space between two knock-over sinkers 8 just in front of a needle 1. Fig. 2 illustrates the moment of the working action in which the presser bar 9, of known construction, presses the hook of the needle against its stem, thereby enclosing the loop 11 just formed by the jack sinker 10, while the loop 12' previously formed and already added to the fabric 12 encircles the stem of the needle just below the point of the hook, owing to the upward movement of the needle. When the needle mounted in needle frame 15 moves down through the encircling loop 12' the latter slips onto the back of hook 2 while bar 9 recedes as illustrated in Fig. 3. This is the moment where the lever arm or finger 7' which has been inactive until now performs its function as a second presser element 70 of the machine. Actuated by cam 4 the finger

advances towards the needle and presses the hook against the stem (Fig. 4), thus enabling the loop to pass over the back of the hook without becoming unduly enlarged through either the hook itself or any other portion of the needle. Cam 4 is so devised and its operation so timed that the pressure of finger 7' against the hook continues until the jack sinker 10 has receded to a point where knocking over of the loops 12' and, hence, the formation of a new row of stitches can take 10 place (Fig. 5).

What I claim is:

1. In a knitting machine of the character described, a needle frame; spring needles mounted in said needle frame; presser bars arranged in front of the hooks of said spring needles; knock-over sinkers arranged between said spring needles underneath said presser bars; additional presser means, consisting of swinging fingers forming one of the arms of a double-armed lever, extending 20 with each of their free ends into the space between two of said knock-over sinkers in front of a needle; and a cam for imparting rocking motion to said double-armed lever.

2. In a flat knitting machine, spring needles 25 for forming the loops; presser members for pressing the needle hooks against the needle stems to enable the passage of the loops from the needle stems to the backs of the needle hooks; and separately mounted additional presser means for 30 maintaining the pressure on the needle hooks until the loops formed on the needles remain uninfluenced in size by the opening-up movement of the needle hooks.

3. In a knitting machine, spring needles for 35 forming the loops; presser members for pressing the needle hooks against the needle stems to enable the passage of the loops from the needle stems to the backs of the needle hooks; and separately mounted additional presser means for 40 maintaining the pressure on the needle hooks until the loops formed on the needles remain uninfluenced in size by the opening-up movement of the needle hooks.

4. The method of preventing the formation of 45 unsightly longitudinal stripes caused by differently sized loops in looped fabrics produced on flat knitting machines operating with spring needles, in which the loops of a row of loops are formed by one thread, which consists in applying 50 closing pressure to the needle hooks during the formation of the loops to enable the passage of the loops from the needle stems to the backs of the needle hooks, and in applying additional closing pressure upon the needle hooks effected separately and independently from the closing pressure first mentioned and after cessation of the latter until the loops formed on the needles remain uninfluenced in size by the opening-up movement of the needle hooks.

5. The method of preventing the formation of 60 unsightly longitudinal stripes caused by differently sized loops in looped fabrics produced on flat knitting machines, particularly of the "Cotton" type, which consists in applying closing 65 pressure to the needle hooks during the formation of the loops to enable the passage of the loops from the needle stems to the backs of the needle hooks, and in applying additional closing pressure upon the needle hooks effected separately and independently from the closing pressure first mentioned, and after cessation of the latter until the loops to be shed have slipped over 70 the tops of the needles.
